UNITED STATES PATENT OFFICE.

HENRY C. MYERS, OF NEW YORK, N. Y., ASSIGNOR TO THE UNITED STATES CIGAR MACHINERY COMPANY, OF NEW YORK.

CIGAR-BUNCH-WRAPPING MACHINE.

SPECIFICATION forming part of Letters Patent No. 397,510, dated February 12, 1889.

Application filed February 21, 1887. Serial No. 228,352. (No model.)

To all whom it may concern:

Be it known that I, HENRY C. MYERS, a citizen of the United States, and a resident of the city, county, and State of New York, have invented a new and useful Improvement 5 in Cigar-Bunch-Wrapping Machines, of which the following is a specification.

My invention relates to improvements in cigar-bunch-wrapping machines in which the 10 cigar bunch is revolved horizontally by means of endless traveling aprons running in opposite directions, and the object of my improvement is to cover the cigar-bunch spirally with a thin wrapper of tobacco-leaf. I attain this 15 object by the mechanism illustrated in the accompanying drawings, in which—

Figure 1 is a side elevation of the machine. Fig. 2 is an end elevation of the machine with a section of the stand broken away. Fig. 20 3 is a vertical section showing cigar-bunch in position to be wrapped. Fig. 4 is a vertical cross-section of Fig. 3 in line X X, showing the cigar-bunch in position between the belts. Fig. 5 is a vertical end view of the upper part 25 of my machine. Fig. 6 is a top view of my machine with the jaws closed. Fig. 7 is a top view of my machine with the jaws open, the lower parts of the machine not being shown.

The different parts of my improved machine are mounted upon and supported by a frame of iron or any other suitable material, such as is shown in the drawings.

Referring to the drawings, L L are two endless traveling aprons, which are mounted 30 upon rollers K K k'' k'' and guide-rollers k''' k'''. The rollers K K and k''' k''' are mounted upon shafts or spindles which turn in bearings in the frame of the machine. The rollers k'' k'' are mounted on shafts or 35 spindles which turn in bearings in the jaws S S. The jaws S S are clearly shown in Figs. 2, 5, 6, and 7. They are pivoted at one end to the frame by the vertical pivots or pins S''' S''', and swing or slide upon the frame 40 horizontally around these pivots as a center, thus moving the rollers k'' k'' and the upper portions of the endless traveling aprons L L away from each other. The jaws S S are limited in their motion and prevented from passing

ing beyond the middle line by the central 50 pivot or stop, V.

k' k' are two rollers, arranged to bear against the endless traveling aprons L L and keep them taut. These rollers k' k' are supported by the links l'' l'', being mounted on shafts 55 which turn in bearings in the ends of the links. The upper ends of the links are pivotally mounted on tie-rods l' l' of the frame. (See Fig. 4.) The rollers k' k' are held against the endless traveling aprons by the spring T, 60 which connects the two links l'' l''.

N is an adjustable bar for holding the cigar-bunch while the wrapper is being wound upon it. On the end of this bar is a revolving pin, n', on which the cigar-bunch is forced 65 and which revolves with the bunch. The pin n' is made long and slender, so that it will penetrate the cigar-bunch far enough to hold it firmly in position and yet will not make a hole in the bunch of sufficient size to injure 70 it or affect its shape when finished. The bar N is supported in its position by a suitable clamping device, O, (see Figs. 3 and 7,) and by means of this clamp the portion of the bar N between the jaws may be lengthened 75 or shortened, and thus adapted to the size of the cigar-bunch to be wrapped. The pin n' may be permitted to revolve by any suitable means, as by being attached to a sleeve which turns upon the bar N. (See Figs. 3 and 7.) 80

Opposite the bar N, at the other side of the machine, is a head-piece, P, for supporting the head or tapered end of the cigar-bunch while the wrapper is being placed upon it, and this head-piece is recessed, as shown in the drawings, the recess being made to conform to the shape of the tapering end of a cigar-bunch. This head-piece is adjustably attached to the frame of the machine by means of the slot p' and the set-screw p', which works in the frame 85 of the machine. By means of this adjustable connection between the head-piece and the frame of the machine the head-piece can be raised or lowered, so as to be fitted or accommodated to the size or thickness of the cigar-bunch. 95

The means which I prefer to employ for operating the jaws S S are clearly shown in the

drawings, and consist of the links S' S', the levers r' r', the rods f'' f'', the chains f' f', and the treadle D, all arranged and combined in the manner shown. The links S' S' are pivoted at one end to the free ends of the jaws S S and at the other end to the levers r' r'. The levers r' r' are each pivoted at their lower ends by means of a screw or pivot, r'', fixed in the frame of the machine. The rods f'' f'' are pivoted at one end to the levers r' r', and at their lower end are pivoted to each other by means of a screw or pivot which is free to move. The chains f' f' are attached at one end to the lower ends of the rods f'' f'' and at their other end to the opposite ends of the treadle D. Between the two rods f'' f'', near their lower ends, is a bar rigidly attached to the frame of the machine for the purpose of preventing the rods f'' f'' from moving laterally or forward and backward. (See Figs. 1 and 2.) The connections between the jaws S and the links S' are so made that the free ends of the jaws are permitted to move in a circular path, while the links move in a more or less straight path. Each of the springs R is connected at one end with each of the levers r' and at the other end to some portion of the frame, and these springs R R operate to draw the levers r' r' toward each other.

Any suitable means may be employed for operating the rollers which support the endless traveling aprons; but I prefer the devices shown in the drawings, which consist of the gear-wheels H W W, the stud or shaft g'', the grooved drive-wheel g', the belt G and grooved drive-wheel C, the treadle D, the springs E, the brackets d', and the pulleys c' c', all combined and arranged in the manner shown. The drive-wheel C is mounted upon the driving-shaft B, upon which is also mounted the driving-wheel A, through and by means of which motion may be imparted to the driving mechanism before described.

M is a rod mounted in the frame of the machine, to which is attached the yoke M', enclosing the endless traveling aprons L L. (See Figs. 1, 3, and 4.) By moving the rod M and yoke M' the endless traveling aprons L L may be shifted on the supporting-rollers, and in this way adjusted to the length of the cigar-bunch which is to be wrapped. The rod M is held in any desired position by any suitable device, such as M''. (Shown in Fig. 5.)

My machine operates in the following manner: The jaws of the machine are first opened by pressing down upon the treadle D, which draws down the chain f' and the rods f'' f'', thus moving the upper ends of the levers r' r' outward and opening the jaws through and by means of the links S' S'. The head-piece P having been properly adjusted with reference to the thickness of the cigar-bunch to be wrapped, and the rod N having been properly adjusted with reference to the length of the cigar-bunch, the cigar-bunch is forced upon the pin n', its head or tapered end rest-

ing in the recess of the head-piece P. The jaws S S are then closed and the endless traveling aprons brought to bear upon the cigar-bunch, causing the bunch to be revolved with the pin n' upon the rod N. To close the jaws, the operator merely releases the treadle D, permitting the springs R R to draw the levers r' r' toward each other, which causes the links S' S' to close the jaws. The endless traveling aprons are made to approach closely to each other below the cigar-bunch by means of the fixed guide-rollers k''' k''', and the endless traveling aprons are made to approach closely to each other above the cigar-bunch by means of the rollers k'' k'', supported in the jaws S S. (See Fig. 4.) It will be seen that the driving mechanism is so connected with the rollers K K that these rollers are made to revolve in opposite directions, and thus the endless traveling aprons are made to move in opposite directions, one apron passing down on one side of the cigar-bunch and the other apron passing up on the other side of the cigar-bunch. When the endless traveling aprons have been closed upon the cigar-bunch and the latter is revolving between them, one end of the wrapper is inserted between the cigar-bunch and the apron having the downward motion at the outer end of the cigar. The end of the wrapper is drawn down between the cigar-bunch and this apron and is caught by the apron on the opposite side and drawn up between that apron and the cigar-bunch, and thus rolled or wrapped around the bunch. The operator guides the free end of the wrapper, moving it toward the head or tapered end of the bunch until the entire bunch has been covered or wrapped spirally with the wrapper. The operator then fastens the outer end of the wrapper by means of gum, or in any suitable way, after which the jaws of the machine are opened and the cigar is removed from the machine.

The driving mechanism of my machine is controlled through and by means of the treadle D and the springs E. When the treadle is pressed down at either end, the pulley c' at the opposite side of the treadle is made to bear against the driving-belt G and to tighten that belt, so that it becomes taut upon the pulleys C and g' and moves with the pulley C and causes the pulley g' to revolve, thus imparting motion to the rollers K K. When the treadle D is released from pressure, the spring E forces it up to a horizontal position, thus loosening the belt G upon the pulley C and stopping the motion of the pulley g'. Motion is imparted to the pulley C by the shaft B and driving-pulley A, mounted upon said shaft.

Various parts of my invention may be used separately or in different combinations. So I do not limit my claim to the combination of all the parts shown.

Other mechanism for opening the jaws and for operating the aprons may be employed without departing from my invention.

It is obvious that, if desired, one of the jaws may be made permanent by simply removing one of the links or rods connecting it with the treadle D. In this case the other 5 jaw only is drawn outward to permit of the introduction or withdrawal of the cigar-bunch. When the cigar-bunch is being inserted or removed, it will of course be necessary to stop the motion of the traveling aprons.

10 It is apparent that the machine may be operated from either side, according as a right-handed or left-handed cigar-bunch is to be wrapped.

What I claim as new, and desire to secure 15 by Letters Patent, is—

1. In a cigar-bunch-wrapping machine, the combination of a holding-pin on which the butt of the cigar-bunch can be pressed, mounted with bearings in the machine in which it 20 revolves, a recessed head-piece for forming and supporting the tip of the cigar movably attached to the machine, so as to be adjustable vertically, an endless traveling apron on each side of the pin and support, rollers to 25 support the aprons, rollers bearing against the aprons to tighten the same, and springs for pressing the tightening-rollers against the aprons, movable jaws pivoted vertically at one end, so as to swing horizontally, and carrying two of the supporting-rollers, guide-rollers on opposite sides of the pin and support, and mechanism for revolving the rollers and 30 operating the jaws, substantially as shown and described.

35 2. In a cigar-bunch-wrapping machine, the combination of a holding-pin onto which the butt of the cigar-bunch can be pressed, mounted with bearings in the machine in which it revolves, a recessed head-piece for supporting and forming the tip of the cigar movably attached to the machine, so as to be adjustable vertically, two endless traveling aprons, one on each side of the holding devices, rollers to support the aprons, rollers bearing 40 against the aprons to tighten the same, and springs for pressing the tightening-rollers against the aprons, a movable jaw pivoted vertically at one end, so as to swing horizontally, carrying one of the supporting-rollers, 45 guide-rollers on the opposite sides of the pin and head-piece, and mechanism for revolving the rollers and operating the jaw, whereby one of the aprons may be moved toward or 50 from the other apron and opened out from or 55 closed upon the holding devices, substantially as shown and described.

3. In a cigar-bunch-wrapping machine, in combination with devices for holding the cigar-bunch at each of its ends, endless traveling aprons, rollers for supporting the aprons, and devices for tightening the aprons, a jaw pivoted vertically at one end, so as to swing horizontally, and carrying one of the rollers,

and guide-rollers on opposite sides of the holding devices, and mechanism for revolving 65 the rollers and operating the jaw, whereby one of the endless aprons can be opened out from the holding devices, substantially as shown and described.

4. In a cigar-bunch-wrapping machine, the 70 combination of a holding-bar for the cigar-bunch, having a revolving sleeve on its end, and a supporting-pin attached to the sleeve, said bar being mounted adjustably in bearings in the machine, two endless traveling 75 aprons, one on each side of the holding-bar, rollers to support and tighten the endless traveling aprons, movable jaws pivoted at one end and carrying the upper supporting-rollers, an adjustable head-piece opposite the 80 holding-bar, guide-rollers on opposite sides of the holding-bar and head-piece, a shifting rod and yoke for moving the aprons, and mechanism for revolving the rollers and operating the jaws, substantially as shown and 85 described.

5. In a cigar-bunch-wrapping machine, a device for holding the cigar-bunch during the operation of wrapping, consisting of a long slender pin adapted to penetrate the cigar- 90 bunch to a considerable distance to hold the bunch in place, and suitable means for supporting the pin so that it can revolve, substantially as shown and described.

6. In a cigar-bunch-wrapping machine, a 95 device for holding the cigar-bunch during the operation of wrapping, consisting of a holding-bar having a revolving sleeve on its end, and a long slender pin attached to the sleeve and adapted to penetrate the cigar- 100 bunch to a considerable distance, sufficiently to hold the bunch in place, said bar being mounted adjustably in bearings in the machine, substantially as shown and described.

7. In a cigar-bunch-wrapping machine, the 105 combination of a cigar-bunch-holding device mounted in bearings in the machine in which it revolves, and adapted to enter the butt-end of the bunch, a head-piece for supporting the tip of the cigar-bunch, two endless traveling 110 aprons, one on each side of the holding devices, rollers to support and rollers to tighten the endless traveling aprons, movable jaws pivoted at one end and carrying the upper supporting-rollers, guide-rollers on opposite 115 sides of the holding devices, a treadle for operating the jaws, and links, levers, rods, and chains connecting the treadle and the jaws, and springs connected with the jaws to act in the reverse direction to the treadle, and mechanism for revolving the aprons and rollers, 120 substantially as shown and described.

HENRY C. MYERS.
